UNITED STATES PATENT OFFICE.

MURRY MILLER, OF NEW YORK, N. Y., AND MAURICE L. KURTZ, OF BOGOTA, NEW JERSEY.

DESIGN FOR A HAND BAG.

Application filed April 28, 1923. Serial No. 5,992. Term of patent 3½ years.

To all whom it may concern:

Be it known that we, MURRY MILLER and MAURICE L. KURTZ, citizens, respectively, of Russia and of the United States, and residents, respectively, of the city of New York, borough of Manhattan, in the county and State of New York, and of Bogota, in the county of Bergen and State of New Jersey, have invented a new, original, and ornamental Design for a Hand Bag, of which the following is a specification, reference being had to the accompanying drawing, forming a part thereof, wherein the figure represents a perspective view of a complete hand bag showing the assemblage of the various novel essentials forming a part thereof.

The design comprises a frame and loop handle decorated with a mat of beads and a clasp also decorated with a mat of beads and a bead fringe depending from the frame simulating a beaded curtain masking the shape and configuration of the pouch of the bag.

We claim:

The ornamental design for a hand bag, substantially as shown and described.

MURRY MILLER.
MAURICE L. KURTZ.
